FREDERIC E. BANFIELD, JR., OF SACO, MAINE, ASSIGNOR TO SACO-LOWELL SHOPS, OF NEWTON, MASSACHUSETTS, A CORPORATION OF MASSACHUSETTS

BOX RAIL AND METHOD OF MAKING SAME

Application filed April 2, 1929. Serial No. 351,991.

This invention relates to rails used in spinning and twister frames to support the bearings or boxes for the spindles. Usually these rails are called "spindle rails" or "box rails", and they will be referred to hereinafter by the latter term.

It has been customary heretofore to make box rails by a metal casting process. Each spinning or twister frame requires at least three rail sections, namely, a head section, a foot section, and an intermediate section. Also, different models and gages of frames require different designs of rail sections, and there must be a separate casting pattern for each section of each gage and length of frame. This obviously requires the use of a large number of patterns. After a box rail casting has been made it must then be machined on its upper, lower and rear faces, which combined with the cost of casting, involves a relatively expensive method of manufacture. The expense is further increased by the fact that there is a high percentage of defective castings due to the peculiar shape and design of the rail sections.

The present invention aims to improve the construction and methods of manufacture of box rails with a view to reducing the expense of manufacture while at the same time providing a superior construction.

The nature of the invention will be readily understood from the following description when read in connection with the accompanying drawings, and the novel features will be particularly pointed out in the appended claims.

In the drawings,

Figure 1 is a perspective view of a series of parts which preferably are used in building a box rail according to the present invention;

Fig. 2 is a front view of a part of a box rail constructed in accordance with this invention;

Fig. 3 is a horizontal sectional view of the rail shown in Fig. 2, the section being taken substantially on the line 3-3, Fig. 2;

Fig. 4 is an end view of the rail shown in Fig. 2;

Fig. 5 is a front view of portions of said rail;

Figs. 6 and 7 are vertical sectional views on the lines 6-6 and 7-7, respectively, Fig. 2; and

Figs. 8 and 9 are sectional views on the lines 8-8 and 9-9, respectively, Fig. 5.

The present method proposes to eliminate the casting process entirely and to make up the box rail sections from metal parts of standard shapes.

Referring first to Figs. 2 to 9, it will be seen that the rail section A there shown comprises upper and lower rail members 2 and 3, respectively, extending longitudinally of the rail in parallel spaced relationship. These members are of angular form in cross section and usually are called "angle irons". Connecting these members at spaced intervals are a series of cross bars indicated by the numerals 4, 5 and 6. Fig. 2 shows both an end section A and part of an intermediate section B of a box rail, and the section A includes an end piece or bar 7, Figs. 2, 4 and 5, which is set at right angles to the other bars. All of these cross bars are welded at their opposite ends to the upper and lower rail members 2 and 3, respectively. It will be observed that one flange of each of the rail members projects horizontally when the rail is in its operative position, and that the other two flanges of said members lie in substantially the same vertical plane and extend toward each other. Also, that these members are held permanently in this relationship by the cross bars, and that the bars 4 are butt welded to the vertical flanges, while the bars 5 and 6 are overlapped upon the vertical flanges and welded to them in this relationship.

The various parts of the rail section A before being assembled are shown in Fig. 1. All of these parts preferably are of steel of standard rolled forms. In a typical instance the angle iron members 2 and 3 may be, say, seven-sixteenths of an inch in thickness and one flange may have a width of approximately one and one-half inches while the other is, say, two and one-half inches wide. The bars 4 correspond in thickness to the stock used in the rail members 2 and 3, but the bars 5 and 6 are made somewhat

thicker. All of these parts are cut to suitable lengths, no other preliminary shaping being required except on the bars 5 and 6. The angle iron members 2 and 3 may conveniently be placed in a suitable form or fixture to hold them in the desired relationship while the cross pieces or bars are arc welded to them. An electric arc preferably, although not necessarily, is used for this purpose.

All of the cross bars cooperate to hold the two rail members 2 and 3 in spaced relationship to each other, but the bars 5, 6 and 7 also serve the additional function of taking the bolts which secure the rail to the samsoms or other frame members of the spinning or twister frame. For this reason the bars 5 are spaced apart by a relatively narrow distance suitable to receive the bolts 8, Figs. 2 and 3, which clamp the rail section to the samsom 9. The bar 6 is located closely adjacent to, but spaced slightly from, the end of the rail section A and the other section B has a bar 6 similarly located, so that when the intermediate and end sections A and B are mounted in their normal positions in the frame, these two bars 6—6 provide a slot between them wide enough to accommodate the bolts 10 which secure the end portions of these two sections to the samsom 12. The fact that these bars 5 and 6 are made somewhat thicker than the bars 4 and have rearward surfaces lying behind the plane of the rearward faces of the upper flanges of the rail members 2 and 3 serves to properly space or position the rail with reference to the samsoms.

The end bar 7 of the rail section A is drilled to take the bolts by which it is secured to the end frame piece of the machine. Preferably this bar is set back slightly from the end faces of the rail members 2 and 3, as best shown in Fig. 5, and a small piece or block 14, Figs. 1, 4 and 5, is welded to the central part of the bar 7 to serve as a bearing or filler piece between this bar and the frame.

When the welding operations have been completed the horizontal flange of the upper rail member 2 is ground on its upper surface, and holes, such as those indicated at 15, Figs. 4 and 6, are punched or drilled through this flange to receive the spindle boxes or bearings. The rear surfaces of the bars 5 and 6 and the extreme end faces of the rail usually also are machined, and holes are drilled for the guide rods for the ring rail. These are, however, the only machining operations usually performed on the rail.

It has been definitely determined in actual practice that this invention effects a very substantial saving in the total cost of manufacture of a box rail. No patterns are required, all of the manufacturing operations

are simplified, and a very large saving in labor is realized. In addition, the rail produced is lighter in weight while being stiffer than the ordinary cast iron rail. Because of this fact there is substantially less breakage of the rails in shipment. A further advantage of this rail construction is that the spaces through it are larger so that it affords additional room to get at and work on the tapes which drive the spindles.

While I have herein shown and described a preferred embodiment of my invention, and a typical method of manufacture of the rail, it will be understood that this description has been made rather by way of explanation than limitation, and that the invention is not limited to the exact details described.

Having thus described my invention, what I desire to claim as new is:

1. In a box rail for spinning and twister frames, the combination of parallel upper and lower longitudinal rail members, said upper member having a flange extending longitudinally thereof at an angle to another longitudinal part of the member and provided with a series of holes to receive the spindle boxes, and a series of bars having their opposite ends welded to said upper and lower members, respectively, and connecting said members permanently together, certain of the bars in said series having portions projecting beyond the parallel rail members and serving to space the box from its frame.

2. In a box rail for spinning and twister frames, the combination of parallel upper and lower longitudinal rail members, each of angular cross sectional form, each of said members having a flange to extend horizontally when the rail is in its operative position, with the other two flanges of said members lying in substantially the same vertical plane and extending toward each other, and a series of bars having their opposite ends welded to the parallel rail members and connecting said members permanently together, one of said bars lying in a plane perpendicular to said vertical plane and being located adjacent an end of the rail members to act as a supporting member for the box rail, the horizontal flange of said upper member being machined on its upper surface and having a series of apertures to receive the spindle boxes.

3. In a box rail for spinning and twister frames, the combination of parallel upper and lower longitudinal rail members, each of angular cross sectional form, each of said members having a flange to extend horizontally when the rail is in its operative position, with the other two flanges of said members lying in substantially the same vertical plane and extending toward each other, and a series of bars having their opposite ends welded to the last named flanges and connecting said members permanently together,

certain of said bars having surfaces lying back of the plane of said vertical flanges and adapted to bear against the samsons of the spinning or twister frame.

5. In a box rail for spinning and twister frames, the combination of parallel upper and lower longitudinal rail members, each of angular cross sectional form, each of said members having a flange to extend horizontally when the rail is in its operative position, with the other two flanges of said members lying in substantially the same vertical plane and extending toward each other, and a series of bars having their opposite ends 10 welded to the last named flanges and connecting said members permanently together, certain of said bars being spaced to provide narrow slots between them to receive bolts for securing the box rail to the samsons of the 15 spinning or twister frame.

5. In a box rail for spinning and twister frames, the combination of parallel upper and lower longitudinal rail members, each of angular cross sectional form, each of said members having a flange to extend horizontally when the rail is in its operative position, with the other two flanges of said members lying in substantially the same vertical plane and extending toward each other, cross bars 20 having their opposite ends butt welded to said last named flanges and connecting said members permanently together, and additional bars, the opposite end portions of which are lap welded to said vertical flanges, the 25 rear surfaces of the latter bars lying behind the plane of the vertical flanges of said upper and lower members, whereby to space the box rail from its support, when in operative position.

40. 6. That improvement in methods of making box rails for spinning and twister frames which consists in providing upper and lower rail members, each of angular cross sectional form and of suitable length, spacing a series 45 of cross bars in predetermined relation to each other, lap-welding the opposite ends of said cross bars to the flanges of said members and thereby securing said members together in parallel spaced relationship to each other with one flange of each member extending 50 toward and lying in substantially the same plane as the corresponding flange of the other member, and with one surface of each of said bars lying in a plane spaced outwardly from the plane of the flanges, and the other flanges 55 of said members extending at right angles to said plane.

7. That improvement in methods of making box rails for spinning and twister frames which consists in providing upper and lower rail members, each of angular cross sectional form and of suitable length, welding the opposite ends of cross bars to the flanges of said members and thereby securing said members together in parallel spaced relationship to

each other, with said bars lying in substantially the same plane as the flanges of said members, welding the opposite ends of an additional cross bar to said members with said additional bar lying in a plane substantially 70 perpendicular to said first mentioned plane, and at some stage in the process forming holes in a flange of one of said members to receive the spindle boxes.

8. That improvement in methods of making box rails for spinning and twister frames which consists in providing upper and lower rail members, each of angular cross sectional form and of suitable length, welding the opposite ends of cross bars to the flanges of 75 said members and thereby securing said members together in parallel spaced relationship to each other, with one flange of each member extending toward and lying in substantially the same plane as the corresponding flange of 80 the other member, and so positioning certain of said bars that their rear surfaces lie behind said plane, whereby to provide a spacing portion on the box rail.

9. In a box rail for spinning and twister frames, the combination of parallel upper and lower longitudinal rail members, each of said members having a flange to extend horizontally when the rail is in its operative position and an additional flange lying in a 90 vertical plane, the two last named flanges of said members being positioned in substantially the same plane and extending toward each other, the horizontal flange of said upper rail member being machined on its upper surface and having a series of apertures formed therethrough to receive the spindle boxes, and a series of cross bars permanently connecting 95 said members and having their opposite ends 100 welded to said members.
